UNITED STATES PATENT OFFICE.

EDWARD ERICKSON, OF LYNN, MASSACHUSETTS, ASSIGNOR TO VICTOR SHOE MACHINERY CO., OF BOSTON, MASSACHUSETTS, A CORPORATION OF MASSACHUSETTS.

MECHANISM FOR ACTUATING THE AWL, NEEDLE, AND NEEDLE-GUIDE OF LOCK-STITCH SEWING-MACHINES.

1,149,352.

Specification of Letters Patent.

Patented Aug. 10, 1915.

Application filed July 17, 1914. Serial No. 852,101.

To all whom it may concern:

Be it known that I, EDWARD ERICKSON, a subject of the King of Sweden, and a resident of Lynn, in the county of Essex and State of Massachusetts, have invented certain new and useful Improvements in Mechanism for Actuating the Awl, Needle, and Needle-Guide of Lock-Stitch Sewing-Machines, of which the following is a specification.

This invention relates to shoe sewing machines, and more particularly to mechanism for actuating the awl, needle, and needle guide of a sewing machine of that type employing a curved hooked needle.

The object of the invention is to provide an improved mechanism for imparting the work-piercing movements to the awl and needle and for moving the needle guide toward the work at the proper time to support the needle.

Another object is to provide means for producing a recession in the movement of the needle near the limit of its movement away from the work so that the thread may be drawn from the barb of the needle by the shuttle without stripping or splitting.

These objects and such others as may hereinafter appear will best be understood from the following description and accompanying drawings of the preferred form of the invention.

Of the drawings: Figure 1 is an end elevation of a sewing machine embodying the present invention. Fig. 2 is a section on the line 2-2 of Fig. 1. Fig. 3 is a detail view looking in the opposite direction from Fig. 1, showing the connection of the driving mechanism with the driven parts. Fig. 4 is a view similar to Fig. 3, showing the parts in another position, and Fig. 5 is a detail view to be hereinafter described.

Similar characters designate like parts throughout the several figures of the drawings.

This invention is illustrated and described as embodied in the shoe-sewing machine shown in a co-pending application, Serial No. 739,056, filed by the present inventor on December 28, 1912, but it is to be understood that the machine of said application is selected for the purposes of illustration

only, and that the invention may be equally well applied to various other sewing machines.

In the drawings, Figs. 1 and 2 show a sewing machine having a base 30 provided with two uprights or standards 31 and 32 carrying a work support 71, and a main cam shaft 34 mounted in suitable bearings 60 carried by the standards and provided with a driving pulley 38. The shaft 34 also has secured thereon a gear 39 which, through connections not shown, actuates a shuttle 53 carrying a bobbin 59. The parts described 65 may be and preferably are identical with the corresponding parts in the aforesaid application, to which reference may be had for a more complete description of the structure not essential to the present invention. 70

As shown in said application, the machine is provided with a needle 151 secured in a carrier 152 (Figs. 3 and 4) mounted to oscillate about a suitable pivot pin and an awl 174 secured in a carrier 173 mounted to 75 oscillate about a pin 175. Suitable mechanism (not shown) is provided to move the awl carrier longitudinally of the pin 175 whereby the work is fed in the usual manner. 80

The present invention contemplates the provision of new and improved means for imparting the oscillating movement to the awl and needle and also to the needle guide. The awl carrier has a radially extending 85 arm 273 on the end of which is pivotally mounted a yoke 171 which is in turn pivotally connected with the upper end of a link 170. The two pivots of the yoke 171, being at right angles to each other, provide for the oscillatory movement of the awl carrier and also for its lateral feeding movement without putting a lateral strain on the link 170. The lower end of the link is connected with an arm 269 adjustably secured to a rock shaft 160 by means of a slotted hub and a clamp screw 260. The rock shaft is extended through the standard 32 (see Fig. 2) and provided with a collar 200 which restrains the shaft from lateral movement. 100 The other end of the shaft carries a disk 158 rigidly secured thereto or, if preferred, the disk may be integral therewith. The disk is mounted in a bearing 161 formed in the

standard 31. The rock shaft is oscillated by a pitman 163 actuated by a crank pin 164 projecting from the side of the gear 39. The connection between the pitman and the 5 rock shaft is preferably made through an arm 201 rigidly mounted on the disk 158. It is apparent that when the shaft 34 is rotated in the direction of the arrow, Fig. 1, the rock shaft 160 will be turned in a direction 10 to move the arm 269 from the position shown in Fig. 3 to the position of Fig. 4, thereby causing the awl to pierce the work.

The needle guide 202 is actuated through connections with the rock shaft 160. A link 15 204, pivotally connected at 203 on an extension of the needle guide, is connected at its lower end at 205 with a short arm 206 formed integral with the arm 269. By this construction the needle guide is actuated by 20 the same means and in timed relation with the awl, although on account of the difference in the length of the radii and the angular position of the arms 269 and 206, the movements imparted to these two parts are 25 wholly different. On the first part of the movement of the rock shaft 160 from the position of Fig. 3, there is very little movement in the needle guide as the arm 206 is then passing dead center, in fact the needle guide 30 may be considered as being at rest as the slight movement does not affect the operation of any of the parts.

In order to actuate the needle, the needle carrier 152 is provided with an arm 154 35 which is connected by a link 155 with an arm 156 fixed on the end of a rock shaft 157 mounted to oscillate in the disk 161. The disk may be provided with a hub 207 to support the inner portions of the rock shafts 40 157 and 160. The outer end of the rock shaft 157 has, adjustably secured thereto, an arm 168 which is connected by a pitman 167 with a crank pin 166 carried by the gear 39. In order that the pitmen 163 and 167 may 45 not interfere, the crank pin 166 is mounted on an arm 208 fixed on the end of the pin 164, the resulting motion being the same as though both pins were mounted directly in the gear 39. For the same reason the arms 50 168 and 201 are offset from each other. The motion imparted to the needle is the result of the combined action of the oscillation of the shaft 157 about its own axis under the influence of the crank pin 166 and its bodily 55 movement about the axis of the shaft 160 as the shaft and disk are oscillated by the crank pin 164. Fig. 5 shows the approximate position of the two rock shafts after about ninety degrees of movement in the 60 gear 39.

It is apparent that various movements 65 may be imparted to the needle by varying the leverage of the actuating parts and the angular relation between certain eccentrically mounted parts, such, for instance, as

the crank pins 164 and 166. It is preferred, however, to so proportion the parts which actuate the needle that the needle will have a recession of movement at about the time it is in its extreme position away from the 70 work. This recession or dip of the needle allows the thread to be freed from the barb of the needle by the action of the shuttle without danger of stripping the thread. It is to be understood that while the connections from the crank pin 166 have been described as the needle actuating mechanism and the connections from the crank pin 164 as the awl and needle guide actuating mechanism, the movement and time of movement 75 80 of the needle is produced by a combined action of the two pins.

It is believed that the operation of this invention will be apparent from the foregoing description and the drawings. The 85 necessary time of operation of the working instrumentalities will be obvious to one skilled in the art. The awl 174 first pierces the work and in so doing assumes the position approximately as shown in Fig. 4. The 90 awl is then moved laterally by any of the usual devices to feed the work and then withdrawn, after which the needle 151 enters the awl hole and the needle guide 202 advances toward the work to support the 95 needle as indicated in Fig. 3. The stitch is formed in the usual manner.

It is believed that the operation and many advantages of this invention will be fully understood from the foregoing description. 100

Having thus described my invention, I claim:

1. In a sewing machine, the combination of a needle; a cylindrical oscillating member having a bearing therein eccentric to the 105 axis of said member; a rock shaft for actuating the needle positioned in said bearing and adapted to be moved therewith; and means for oscillating said rock shaft about its own axis.

2. In a sewing machine, the combination of an awl, a rock shaft for actuating the awl, a needle, a rock shaft for actuating the needle, and means for moving the needle rock-shaft bodily with the oscillation of the 115 awl rock shaft.

3. In a sewing machine, the combination of an oscillating needle; a needle guide; an awl; means for oscillating said awl; and means actuated by said awl oscillating 120 means for positively and continuously oscillating said needle guide during the oscillation of said awl.

4. In a sewing machine, the combination of a needle and a needle guide, and means 125 for actuating the needle guide comprising a link connecting the needle guide with a pin adapted to oscillate in an arc of a circle and arranged to pass the dead center when the needle guide is advanced toward the work. 130

45

5. In a sewing machine, the combination of a needle, a needle guide and an awl, a rock shaft, a member secured thereto having two arms, a link connecting the awl with one arm, and a link connecting the needle guide with the other arm.

6. In a sewing machine, the combination of a needle, a needle guide and an awl, a rock shaft, two arms mounted thereon, a link connecting the awl with one of the arms on the rock shaft, a link connecting the needle guide with the other arm on the rock shaft, and means for actuating the rock shaft to cause the needle guide link to pass 15 a dead center.

7. In a sewing machine, stitch forming mechanism including a shuttle and a curved hooked needle, a shaft having two cranks, a rock shaft mounted to swing, a pitman connecting one of said cranks to swing said rock shaft, a second pitman connecting the other crank with the rock shaft to oscillate it, and a connection from said rock shaft to the needle carrier to irregularly actuate the 25 latter.

8. In a sewing machine, stitch forming mechanism including a shuttle and a curved hooked needle, an oscillating awl, a shaft having two cranks, a rock shaft mounted to swing, a pitman connecting one of said cranks to swing said rock shaft, a second pitman connecting the other crank with the rock shaft to oscillate it, a connection from said rock shaft to the needle carrier to irregularly actuate the latter, and connections whereby the awl is oscillated by the swing- 35 ing support for said rock shaft.

9. In a sewing machine, an oscillating needle and an oscillating awl, a pair of pit- 40 men, cranks for actuating said pitmen, a swinging support, connections from said swinging support to the awl carrier to actuate the latter, a rock shaft mounted in said

swinging support, and connections from said rock shaft to the needle carrier.

10. In a sewing machine, the combination of a needle; a needle guide; an awl; an oscillating member; and means connected with said oscillating member for imparting positive and continuous movement to said needle 50 guide and awl simultaneously.

11. In a sewing machine, the combination of a needle; a needle guide; an awl carrier; an oscillating member having two lateral projections; a link between one projection 55 and the awl carrier; and another link between the other projection and the needle guide.

12. In a sewing machine, the combination of a needle; a needle guide; an awl carrier; 60 an oscillating member having two lateral projections at different distances from the axis of said oscillating member; a link between the outer projection and the awl carrier; and another link between the inner 65 projection and the needle guide.

13. In a sewing machine, the combination of an oscillating needle; a needle guide; an awl; and a single means for positively and continuously actuating said needle guide 70 and awl at different speeds for predetermined periods.

14. In a sewing machine, the combination of an oscillating needle; a needle guide; an awl; and a single means for positively and 75 continuously oscillating said awl for a predetermined period and simultaneously actuating said needle guide positively and continuously during the oscillation of said awl.

Signed by me at Boston, Mass., this 18th 80 day of June, 1914.

EDWARD ERICKSON.
